DEBUTANIZATION OF NAPHTHA

Jackson R. Schonberg and Willard E. Robinson,
Westfield, N. J., assignors to Standard Oil De-
velopment Company, a corporation of Dela-
ware

Application November 10, 1930, Serial No. 494,587

2 Claims. (Cl. 196—11)

This invention relates to the removal of undesired low boiling components from hydrocarbon oil and more particularly to the debutanization of naphtha.

- 5 The invention will be fully understood from the following description taken in connection with the accompanying drawing, in which latter the figure is a diagrammatic showing of a preferred form of the invention.
- 10 Referring particularly to the drawing, reference numeral 1 designates a bubble tower which contains a plurality of plates having openings and bell caps associated with the plates at the openings. The bubble tower is connected with a cracking system by means of line 2 through which the products of the cracking reaction are adapted to be passed into an intermediate portion of the bubble tower wherein they are fractionated. Coolers 3 and 4 are provided in the bubble tower 15 and a reboiler 5 is provided in the lower portion of the bubble tower. Feed stock for the cracking process is preferably used as the cooling medium in 3 and 4. Steam can be introduced into the lower portion of the bubble tower through line 6. Bottoms are withdrawn from the bubble tower through line 7 for recycling to the cracking reaction or for other utilization. The hydrocarbons in the tower are maintained under a pressure of approximately 120 lbs. per square inch 20 and are withdrawn from the tower at a temperature of approximately 190° F. A naphtha and/or heavy naphtha side stream can be withdrawn from an intermediate portion of the bubble tower through a line 8 and passed through a steam stripper 9, where vapors consisting of steam and light ends are separated from the naphtha and are returned to the bubble tower through a valved line 10. As shown in the drawing, there is preferably no run-down from the plate supplying liquid to line 8; that is, the first stage fractionation in the lower part of tower 1 is conducted only with reflux supplied by coil 3. Steam is introduced into the steam stripper through a line 11. The side stream from the bubble tower is 25 the product of a second stage fractionation in the upper part of the tower and constitutes roughly half of the pentane formed in the cracking reaction and all of the heavier components boiling within the naphtha and/or heavy naphtha range. It will be understood that where butane, pentane, and other saturated hydrocarbons are referred to, their isomers and unsaturated hydrocarbons of the corresponding boiling range are also included. The bottoms from the stripper 30 withdrawn through a line 12 constitute hydrocarbons substantially free from butane and lighter constituents. The bubble tower can be the single or the secondary bubble tower of a cracking system.
- 35 Overhead product containing roughly half of the total pentane formed in the cracking reaction and all of the lighter components, together with similar components which are returned as reflux to the upper part of tower 1 is withdrawn from the tower through a line 13. This line communicates with a condenser 14 in which the overhead is cooled to a temperature of approximately 115° F. and is discharged into a container 15. The steam and light ends from steam stripper 9 can be introduced directly into condenser 14 through a valved line 15' when desired. The condensate is passed through a line 16 to a separator 17 where any water present is separated from the condensate. The separated condensate is passed by means of a pump 18 and line 19 into the upper portion of the bubble tower to function as reflux liquid.
- 40 Uncondensed vapors pass from container 15 through a line 20 and compressor 21 where they are compressed to a pressure of approximately 250 lbs. per square inch. The compressed vapors are cooled in a condenser 22 to a temperature of approximately 80° F. whereby portions of the compressed vapors are condensed. The condensate is collected in a receptacle 23. The vapors 45 are passed from receptacle 23 through a line 24 and compressor 25 where they are compressed to a pressure of approximately 500 lbs. per square inch. The thus compressed vapors are cooled in a condenser 26 to a temperature of approximately 80° F. whereby a second condensate is formed which accumulates in receptacle 27. The gases or uncondensed vapors pass from receptacle 27 through a line 28 to an absorption plant 29 where liquid constituents are derived from the gases. 50 The residual gases are withdrawn from the absorption plant through a line 30 to a burning line, or other suitable place of disposal, not shown. Alternatively the vapors from the bubble tower can be compressed in one stage instead of in two stages to condense most of the heavier constituents and some of the advantages of the invention will be retained.
- 55 The condensates contained in receptacles 23 and 27 are conducted through valved lines 32 and 33 respectively, into a bubble tower 35. Liquid derived from the absorption plant 29 can be returned to line 33 through a line 36. Line 33 opens into the bubble tower above the place of entrance of the condensate through line 32.

Bubble tower 35 contains a plurality of perforated plates and bell caps, not shown. The light naphtha bottoms in the bottom of bubble tower 35 are reboiled by means of heat derived from indirect heat exchange with the bottoms obtained from the steam stripper 10. These bottoms are introduced into the bubble tower through the line 12 and are withdrawn therefrom through a line 39 to cooler 40. This debutanized naphtha can be treated, rerun and stored without appreciable evaporation losses. The light naphtha is rectified in bubble tower 35 under a pressure of approximately 190 lbs. per square inch and leaves the bubble tower at approximately 100° F. Reboiling of the naphtha in the lower portion of the tower is effected by means of the auxiliary reboiler 41 into which the naphtha is introduced from the tower through a line 42 and is returned to the tower through a line 43. Vapors leave the tower through a line 44 and are cooled in a condenser 45 to a temperature of approximately 80° F. The resulting condensate is accumulated in a receptacle 46 and is returned to the upper portion of the tower through a line 47. Gases are discharged from receptacle 46 through a line 48.

The stabilized light naphtha bottoms are withdrawn from the bubble tower 35 through a line 50 and cooler 51 and constitute a stabilized naphtha having an end boiling point of approximately 300° F. This stabilized light product can be refined, if necessary, and blended with the debutanized naphtha discharged through line 39 or can be blended with natural naphtha as desired.

While it has been described that reflux liquid for tower 1 has been provided from condenser 14, it will be understood that under certain conditions reflux liquid may not be returned from this point, but can be obtained from the condensate in receptacle 23 or can be obtained from the stabilized naphtha derived from cooler 51.

By the process described, naphtha such as cracking coil gasoline is substantially freed of butanes with the recovery and stabilization of the lighter components of the gasoline.

The temperatures and pressures stated herein are based on a cooling water temperature of approximately 70° F. If the latter temperature varies, there will be a corresponding variation in the conditions of operation.

Various changes may be made within the scope of the appended claims, in which it is desired to claim all novelty inherent in the invention as broadly as the prior art permits.

We claim:

1. A process of separating naphtha from a mixture containing hydrocarbons boiling within the naphtha range, together with non-condensable gas, into debutanized and stabilized fractions comprising separating the naphtha by fractionation in a fractionating zone into a liquid heavy naphtha and a first vapor containing light naphtha hydrocarbons together with non-condensable gas, compressing the first vapor and cooling the same in a cooling zone maintained under high pressure to produce a condensed light naphtha fraction and a second vapor containing non-condensable gas, passing the second vapor through an absorption system in which naphtha constituents are recovered and non-condensable gas is removed, and introducing the naphtha constituents recovered from the first vapor and the second vapor into a stabilizing zone in which further non-condensable gas is removed by rectification. 25

2. A process of separating naphtha from a mixture containing hydrocarbons boiling within the naphtha range, together with non-condensable gas, into debutanized and stabilized fractions comprising separating the naphtha by fractionation in a fractionating zone into a liquid heavy naphtha and a first vapor containing light naphtha hydrocarbons together with non-condensable gas, cooling said first vapor to recover therefrom a liquid fraction, returning said liquid fraction to said fractionating zone as reflux, compressing the first vapor and cooling the same in a cooling zone maintained under high pressure to produce a condensed light naphtha fraction and a second vapor containing non-condensable gas, passing the second vapor through an absorption system in which naphtha constituents are recovered and non-condensable gas is removed, and introducing the naphtha constituents recovered from the first vapor and the second vapor into a stabilizing zone in which further non-condensable gas is removed by rectification. 35 40 45
